UNITED STATES PATENT OFFICE.

ALFRED LADNER, OF PHILADELPHIA, PENNSYLVANIA.

DESIGN FOR A WATCH-CHAIN.

SPECIFICATION forming part of Design No. 21,110, dated October 13, 1891.

Application filed September 10, 1891. Serial No. 405,328. Term of patent 7 years

To all whom it may concern:

Be it known that I, ALFRED LADNER, a citizen of the Republic of France, and a resident of Philadelphia, Pennsylvania, have invented 5 a Design for a Watch-Chain, of which the following is a specification.

My design for a watch-chain is fully illustrated in the accompanying drawing.

The main feature of my design is the representation, in miniature, of the tools used by butchers, connected together by links, forming a chain.

The snap *a* is at one end of the chain. *b* is the representation, in miniature, of a butcher's steel connected to the snap by a chain. *c* represents, in miniature, a cleaver. *d* repre-

sents a butcher's knife. *e* represents a butcher's saw, the whole being connected together by links of chain, and *f* represents, in miniature, a pair of horns forming the bar for the 20 watch-chain and connected to the saw by links.

I claim—

The design for a watch-chain, as herein shown and described. 25

In testimony whereof I have signed my name to this specification in the presence of two subscribing witnesses.

ALFRED LADNER.
